3 Sheets-Sheet 3

Fig. 8. A circuit diagram showing a power source (18) connected to a vertical line (19). This line (19) connects to a junction point (42) on the left. From this junction point (42), two horizontal lines branch out: one to the left labeled (38) and one to the right labeled (58). The line (38) leads to a switch (42') which connects to a junction point (42''). The line (58) leads to a junction point (57) which connects to a switch (26). From the junction point (57), a line (25) leads to a junction point (58) on the right. From this junction point (58), a line (29) leads to a junction point (59) on the right. From the junction point (59), a line (67) leads to a junction point (66) on the right. From the junction point (66), a line (42'') leads to a junction point (38) on the right. From the junction point (38), a line (42') leads back to the junction point (42). A resistor (55) is connected in parallel across the junction points (58) and (25). A switch (20) is connected in parallel across the junction points (27) and (28). A switch mechanism (a, b, c, d, e, f) is connected between the junction points (28) and (29). A resistor (50) is connected in series with the junction point (59).

UNITED STATES PATENT OFFICE.

ARNOLD ZUKOR, OF NEW YORK, N. Y.

TRAIN-OPERATED RAILWAY GATE.

Application filed April 13, 1925. Serial No. 22,617.

The present invention relates to improvements in train-operated railway gates, that is to say to crossing gates which are closed by the approach of a train toward the crossing and opened by the train as it passes beyond the crossing. The invention pertains more particularly to railway gates which are adapted to be employed in connection with the automatic railway signal and stop system described in U. S. Letters Patent No. 1,505,459, granted to me on August 19, 1924. In this patent a railroad signal is described which includes a plurality of boxes disposed along a track, each box having slidably arranged therein a stop which extends above the upper surface of the same. A shoe is slidably disposed above each box. There are means provided for connecting each shoe with the stop in the box in rear of it, whereby, upon lowering a shoe, the stop connected therewith is raised. Within each box there is a means disposed for causing the shoe thereon to be raised when the stop in the same box is raised.

The main object of the present invention is to provide a crossing gate which is actuated by an electric motor, the latter being disposed in electric circuits which are controlled by switches operated by the shoes of the railroad signal above referred to, means being provided for reversing the direction of rotation of said motor, the said reversing means being set in operation by the railway gate.

A further object of the invention is to construct the mechanism that it can be conveniently installed on already existing tracks provided with the railroad signal above referred to, more particularly without necessitating material changes in the construction of the said signals or in the construction of the track itself.

A further object of the invention is to provide a railway gate of the character mentioned wherein an electric signal is actuated cautioning those arriving at the gate when the latter is about to be set to closing position.

With these and other objects in view, which will more fully appear as the nature of the invention is better understood, the same consists in the combination, arrangement and construction of parts hereinafter described, pointed out in the appended claims and illustrated in the accompanying

drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a diagrammatic view of the invention employed on a single-track road; Fig. 2 is a side elevation, partly in section, of the gate and its operating mechanism; Fig. 3 is a section taken on line 3-3 of Fig. 2, on a larger scale; Fig. 4 is a section taken on line 4-4 of Fig. 2, also on a larger scale; Fig. 5 is a side elevation of a portion of a locomotive with an element thereon for actuating the electric signalling system and the circuit closing means of the motor of the gate closing device; and Figs. 6 to 8, inclusive, are diagrams of the electric circuits, the movable elements of the latter being shown in the figures in different positions.

Referring now to the drawings, the numeral 10 indicates a railroad track, on which the trains run in the direction of the arrow shown in Fig. 1 of the drawings. A gate post 11 is mounted adjacent the track at a crossing, and to this post is pivoted at 12 a railway gate 13, comprising a plurality of links 14, which are joined to form a lazy-tong construction. The gate post 11 is disposed on one side of the road at the crossing, and in alignment therewith is disposed the other side of the road a post 15, the gate being adapted to extend from post to post, as clearly shown in Fig. 2 of the drawings. The outermost links of the lazy-tong construction are pivoted to a vertically extending bar 16, to the lower end of which is fixed a horizontally extending toothed rack 17, the said rack being slidably disposed in a guide 18, which is located in the ground. The teeth of this rack mesh with those of a pinion 19, which is mounted on the shaft of an electric motor 20. In the path of the toothed rack are disposed two levers 21 and 22, pivoted at 23 and 24, respectively, to some support below the guide 18. These levers are connected by a bar 25, carrying four switch blades, denoted by the numerals 26, 27, 28 and 29. These blades are electrically

insulated from one another. With these switch blades are associated stationary contact points, as will hereinafter appear.

The railroad track is divided for signaling purposes into sections or blocks, the division being accomplished by placing at predetermined intervals along the track signaling devices, denoted in Fig. 1 of the drawings by the numerals I, II and III. The 10 signaling devices I and II are disposed a suitable distance in front of the railway gate, and the signaling device III a suitable distance beyond the same. These devices are all alike in construction and are described 15 in detail in U. S. Letters Patent No. 1,505,-459, granted to me on August 19, 1924. Each of the same comprises a box 30', with which are associated two cylinders 30 and 31, which do not communicate one with the other. These cylinders are sunk into the ground adjacent the track. The cylinder 30 of each set is connected by a pipe 32 with the cylinder 31 associated with the next box in the rear. With each cylinder 31 is associated 20 a stop 33, comprising a vertical bar projecting above the cylinder and mounted upon a piston rod 34, the latter extending into the cylinder and carrying within the same a piston 35, reciprocably mounted therein. In each cylinder 30 is also reciprocably mounted a piston, denoted by the numeral 36, the rod 37 of which extends above the box and carries at its free end a shoe 38. On the piston rods 37 and 34 are 25 mounted arms 39 and 40, respectively, which extend toward each other, as clearly shown in Fig. 1 of the drawings, their free ends overlapping. The cylinders and the pipes 32 are filled with a suitable liquid. The 30 locomotive, indicated by the numeral 41 in Fig. 5 of the drawings, carries a roller 41', adapted to co-operate with the shoes 38. When a train arrives at a signal box and the track is clear ahead of it, the parts of 35 the signal box are in the positions I, shown in Fig. 1 of the drawings, in which the shoe 38 is in its raised operative position and the stop 33 in its lowered inoperative position. As the locomotive runs past the signal box I, its roller 41' depresses the shoe 38. As this shoe moves downwards, the piston 36 in the cylinder 30 forces the liquid from this cylinder into the pipe 32 communicating therewith, the liquid being 40 forced into the cylinder 31 in the signal box in the rear, moving the piston 35 therein upwards, thus raising the stop in said box to its operative position. The arm 40 of this stop acts on the arm 39 of the shoe associated with the same box and thereby also raises the said shoe. From this it appears that, whenever a locomotive depresses the shoe 38 of a signaling box, the stop of the box in rear of the series is raised. By raising 45 this stop, the shoe of the same box is also

raised. At the same time, however, the stop in the rear of the last-named box is restored to its normal inoperative position, due to the partial vacuum created below its piston.

The shoes 38 of the three signal boxes shown in Fig. 1 of the drawings are made of metal and with each of the same co-operate two stationary contact points 42, 42' and 42'' which are adapted to be bridged over by the said shoes, the said contact points being inserted in electric circuits, as will hereinafter appear.

Adjacent the railway gate is mounted on one side of the track a post 43, carrying an electric sign 44. This sign comprises a casing 45 having translucent sides 46, on each of which is inscribed a legend 47, to give warning to those approaching the crossing when the gate is about to be closed. Within the casing is disposed an electric lamp 48, arranged in an electric circuit 49, the latter including a source of electric energy 50 and the two contact points 42 associated with the shoe 38 of the signal box I. On each of the sides 46 of the casing may also be disposed a 55 bull's eye 51. When the locomotive of a train arrives at the signal box I and depresses the shoe 38 thereof, the latter bridges over the contact points 42, thereby closing the circuit 49 of the lamp 48, which thus illuminates the electric sign. This circuit is closed until the locomotive depresses the shoe 38 of the signal box II, when the stop 33 of the signal box I is raised and carries with it the shoe 38, so that the circuit of the electric lamp 48 is opened.

Below the bar 25 is mounted a panel 52, and on the latter are disposed contacts with which co-operate the switch blades 26, 27, 28 and 29. The blades 27 and 28 co-operate 105 each with a set of three contact points, denoted by the numerals 53 and 54. The contact points of the set 53 are indicated by the reference characters *a*, *b* and *c*, and the contact points of the set denoted by the numeral 54 are indicated by the reference characters *d*, *e* and *f*. The contact points *a*, *c*, *d* and *f* are connected by conductors with the brushes of the motor 20, while the contact points *b* and *e* are connected with the terminals of the field 55 of the motor, (see Figs. 6 to 8, inclusive, of the drawings). With the switch blade 26 co-operate contact points 56 and 57, and with the switch blade 29 contact points 58 and 59. All of these are mounted 110 on the panel 52. The contact point 56 is connected by a conductor 60 with one of the terminals of the field 55 of the motor, and the contact point 57 is connected by a conductor 61 with one of the terminals of the 115 battery 50. Similarly is connected the contact point 58 with the other terminal of the field 55 by a conductor 62, and the contact point 59 is connected by a conductor 63 with the other terminal of the battery 50. 120

- The contact points 56 and 57 are also connected by conductors 64 and 65, respectively, with the contact points 42', which are associated with the shoe of the signal box II.
- 5 The contact points 58 and 59, on the other hand, are connected by conductors 66 and 67, respectively, with the contact points 42'', associated with the shoe 38 of the signal box III.
- 10 The operation of this device is as follows: When the gate is in its folded, that is to say in its open position, and a train has passed the signal box I, the movable elements of the several switches of the device are in 15 the positions indicated in the diagram shown in Fig. 6 of the drawings. From this diagram it appears that the shoe 38 of the signal box I is in its depressed condition, so that the electric sign 44 is illuminated. The shoe 20 38 of the signal box II is in its raised position and the switch blade 26 in its open position, so that the electric circuit of the motor is interrupted. As soon as the roller 41' rides over the shoe 38 of the signal box II 25 and depresses said shoe, the contact points 42', 42'' are bridged over, whereby the motor circuit is closed. This motor, in its rotation, actuates the toothed rack 17, causing the lazy-tong mechanism to be extended so that 30 the elements are brought into the positions shown in Fig. 2 of the drawings. As this toothed rack moves, it shifts the levers 21 and 22 into the positions shown in Fig. 2 of the drawings, whereby the contact points 35 56 and 57 are bridged over and a cap created between the contact points 58 and 59, (Fig. 7). At the same time the switch blades 27 and 28 are shifted so as to bridge over the contact points *a* and *b*, and the contact 40 points *d* and *e* respectively, they having been previously in the positions indicated in Fig. 6 of the drawings. By so shifting the blades 27 and 28, the direction of the current flowing through the armature of the motor is 45 reversed. It is to be noted, however, that inasmuch as the circuit has been interrupted between the contact points 58 and 59, the motor circuit has been interrupted, so that the gate will be held in its extended position 50 shown in Fig. 2 of the drawings. When now the locomotive arrives at the signal box III, the shoe 38 of the latter is depressed so that the contact points 42'', 42''' are bridged over, with the result that the motor circuit is 55 closed, the motor rotating in a direction opposite to that in which it extended the folding gate. The gate is thus folded. As it arrives at its folded position the rack 17 comes in contact with the lever 21, shifting the bar 25 whereby the polarity of the motor is again reversed and the contact points 58 and 59 are bridged over by the blade 29, and a gap is made between the contact points 56 and 57, (Fig. 8). The device is thus ready for the next train. It is to be noted that 65 when the shoe 38 of the signal box III is depressed, the shoe 38 of the signal box II is raised, making a gap between the contact points 42'', 42''. The shoe 38 of the signal box III will be raised when the shoe of the 70 next signal box in the series is depressed.
- What I claim is:—
1. In a train-operated railway gate, the combination with a post, of a gate mounted thereon consisting of a plurality of jointed 75 links forming a lazy-tong construction, an electric motor for extending and folding said lazy-tong construction, a track switch in the circuit of said motor in front of said gate, a track switch in the circuit of said motor 80 beyond said gate, a motor reversing switch, a circuit interrupter, said motor reversing switch and said interrupter being actuated by said gate, and means interconnecting said two track switches for restoring the track 85 switch in front of said gate to open position, by the act of closing of the track switch beyond said gate, and means for restoring the track switch beyond said gate to open position after the train has traveled a pre-determined distance beyond said last-mentioned track switch.
  2. In a train-operated railway gate, the combination with a post, of a gate mounted thereon consisting of a plurality of jointed 95 links forming a lazy-tong construction, a toothed rack connected to the outermost links of said lazy-tong construction, an electric motor for actuating said toothed rack, a track switch in the circuit of said motor 100 in front of said gate, a track switch in the circuit of said motor beyond said gate, a motor reversing switch, a circuit interrupter, said motor reversing switch and said circuit interrupter being actuated by said toothed 105 rack, means interconnecting said two track switches for restoring the track switch in front of said gate to open position by the act of closing of the track switch beyond said gate, and means for restoring the track switch beyond said gate to open position after the train has traveled a predetermined distance beyond said last-mentioned track switch.
- Signed at New York, in the county of 115 New York, and State of New York, this 7th day of April, A. D., 1925.
- ARNOLD ZUKOR.
